UNITED STATES PATENT OFFICE

CARL EKBERG, OF LOMBARD, ILLINOIS

DESIGN FOR A DISPLAY BOX FOR TOOLS

Application filed May 25, 1931. Serial No. 39,962. Term of patent 3½ years.

To all whom it may concern:

Be it known that I, CARL EKBERG, a citizen of the United States, residing at Lombard, in the county of Du Page and State of Illinois, have invented a new, original, and ornamental Design for a Display Box for Tools, of which the following is a specification, reference being had to the accompanying drawing, forming part thereof.

As shown in the drawing:

Figure 1 is a top plan view of a display box for tools showing my new design;

Figure 2 is a bottom plan view of the same; and

Figures 3 and 4 are end views shown on an enlarged scale.

This ornamental display box for tools is intended particularly for holding and displaying tools such as sets of socket wrenches.

I claim:

The ornamental design for a display box for tools, as shown.

CARL EKBERG.
